GOTTHILF ANSGARIUS BETULANDER, OF SÖDERTÖRNS VILLASTAD, SWEDEN, ASSIGNOR
TO THE BETULANDER AUTOMATIC TELEPHONE COMPANY, LIMITED, OF LONDON,
ENGLAND.

SELECTOR-SWITCH.

1,184,162.

Specification of Letters Patent.

Patented May 23, 1916.

Application filed March 14, 1913. Serial No. 754,273.

To all whom it may concern:

Be it known that I, GOTTHILF ANSGARIUS BETULANDER, a subject of the King of Sweden, and resident of Södertörns Villastad, in the Kingdom of Sweden, have invented certain new and useful Improvements in Selector-Switches, of which the following is a specification, reference being had therein to the accompanying drawings.

- 10 The invention relates to selector switches provided with individual, electro-magnetic driving devices. In selectors of that class the selective shifting movement is usually effected directly by means of an electro-magnetic step-by-step acting mechanism, while the restoring of the selector is effected by spring force or by gravity. Such selectors may be reliable, it is true, when operated at moderate speeds. At high speeds, however, 15 they lose in security of service owing to the fact that a relatively great mass is to be accelerated at every advancement, so that impulses of current may be lost. Furthermore, great shifting speeds may cause inadmissible stresses prejudicially affecting the adjustment and reducing the length of life of the selector. In order to attain great shifting speeds without the said disadvantage one has tried to provide means for imparting to 20 the line contacts a continuous selective movement, as is in itself well known already long ago. For instance, it has been proposed to use a solenoid in such a manner that the line contacts are shifted continuously by the 25 movable core of the solenoid being attracted and are restored to normal position by spring force. However, such a selector has several inconvenient features. In some forms of solenoid selectors, for instance, it 30 is necessary to keep the solenoid or an electro-magnet current carrying during the conversation which causes a considerable loss of current. This said disadvantage may be overcome, it is true, in other constructions 35 but the selector is thereby made more complicated or less reliable in operation.

A simple and reliable selector is obtained according to this invention by reversing the driving conditions in the selectors in the 40 class in question, so that the selective movement is effected by means of spring force or gravity while the restoring of the selector is effected by direct action of the electro-magnetic driving device. By so constructing the

selector no power is, obviously, consumed in keeping the selector in shifted position as the line contacts may be stopped against the action of the spring force or gravity or by cutting off the motive power. The consumption of electric power occurs only at the restoring of the line contacts to normal position and corresponds closely to the amount of power necessary for the shifting of the selector. Furthermore, in a selector according to this invention an ordinary electro-magnetic step-by-step acting device may be used as the source of power of the selector, while in a selector where the continuous selective movement is to be effected directly by the electro-magnetic driving device, a solenoid is inevitable which is more complicated and more expensive than an ordinary electro-magnet. A step-by-step acting driving device is so much the more advantageous as the above mentioned disadvantages of step-by-step mechanisms are entirely omitted in 55 selectors according to the present invention inasmuch as the restoring operation may be performed at a lower rate than the selective operation. In addition, by using spring force or gravity the motive power for the 60 selective movement will be more uniform, whereas the tractive power of a solenoid varies during the movement of the core.

The invention refers especially to pre-selectors or similar selectors for automatic telephone exchanges but may for instance also be applied to group-selectors. A group-selector may, advantageously, be so arranged that the line contacts are first shifted in known manner step by step in one direction to select a certain group of lines and then, according to this invention, are moved continuously in a direction perpendicular to the direction first mentioned to hunt for a 70 engaged line of the said group.

The invention is illustrated in the accompanying drawings, which show two forms of the same. Figure 1 shows schematically a pre-selector with rectilinear shifting movement and Fig. 2 a pre-selector with rotating movement. Fig. 3 is a side view of a part of the selector, shown in Fig. 2.

The pre-selector shown in Fig. 1 is arranged as follows. In a stationary plate 1 two studs 2 are fixed, to which a frame 3 is pivoted. A connecting rod 6 is slidably mounted in the two shanks 4, 5 of the said

frame, which rod carries at its top end contact springs 7 and 8, insulated from the rod, and a spring 10, provided with a roller 9, which is held in constant contact with the corresponding part of the contact field of the selector. The object of the said roller is to examine if the lines of the field are engaged or not engaged. Two electro-magnets 11 and 12 (the working electro-magnet and the auxiliary electro-magnet respectively) are fixed to the frame 3. The electro-magnet (11) first mentioned alone effects the adjustment of the connecting rod 6 and in co-operation with the other electro-magnet (12) the returning of the same. The armature 13 of the electro-magnet 11 is pivoted to the frame 3 and carries at its free end a lever-arm 14, which acted upon by a spring 15 fixed to the shank 4, keeps the armature 13 in raised position and 20 a pawl 16, pivoted to the lower end of the lever-arm 14, in engagement with the teeth 17 of the connecting rod 6. To the lower end of the lever arm 14 is fixed a pin 18, which slides along an oblique surface 19 on the 25 electro-magnet 11. The armature 20 of the electro-magnet 12, which has the shape of a bell crank lever and is pivoted at 21, is forced by a spring 22 against the lower end of the lever arm 14 and is provided with a pawl 24, 30 acted upon by a spring 23. The movement of the pawl 24 away from the top part of the armature 20 is limited by a screw 86 extending freely through the pawl and in screw-threaded engagement with the armature 20, the head of which thus limits the movement in the said direction, so that, as the armature 13 is attracted by the electro-magnet 11, the pawl 16 as well as the pawl 24 are brought out of engagement with the teeth 35 17 of the connecting rod 6 by the spring 22. To the lower part of the plate 1 is fixed an electro-magnet 25 (the disconnecting electro-magnet), the armature 26 of which is pivoted to the shank 5 and provided at its free end 40 with a pawl 27, which acted upon by a spring 28 fixed to the armature 26, is held in engagement with the teeth 29, provided on the lower end of the connecting rod 6. A screw 30 is provided on the shank 5. The 45 armature 26, when attracted by the electro-magnet 25, strikes the said screw, before it arrives to the surface of the pole of the electro-magnet, which results in the frame 3 and the parts carried by the same being moved by the armature 26 and the contact springs 7 and 8 being brought out of contact with the corresponding contact-field. The movement of the frame 3 is limited by a pin 31 fixed in the plate 1. The frame 3 is moved in the 50 opposite direction by a spring 32, fixed in the frame 3 and the plate 1, and this movement is limited by a pin 33, fixed in the plate 1. In the position determined by the pin 33 the contact springs 7 and 8 are in contact 55 with the corresponding contact field. To the

outer end of the shank 5 is fixed an angular piece 34, to the lower end of which is pivoted an anchor escapement 35, which co-operates with teeth 36 on the connecting rod 6 for causing the said rod, when released and moved downward by its weight to fall at a speed as uniform as possible. 70

On the shank 5 is provided a group of contact springs 37, 38, 39, 40, 41, 42, 43, 44, acted upon by the armature 20, while on the shank 4 are provided a group of contact springs 45, 46, 47, 48, acted upon by the armature 13, and a group of contact springs 49, 50, 51, 52, acted upon by the connecting rod 6. In addition to the said groups of contact springs a group of contact springs 53, 54, 55 is provided, which is acted upon by the frame 3. 80

The pre-selector operates in the following manner. As the subscriber causes his number switch to operate in order to provide a connection for conversation one 56 of the line branches is connected with earth. In this manner an impulse of current is sent through line 56, line 68, contact spring 39, contact spring 40, line 58, the winding of the electro-magnet 11, wire 59 and battery 75, which results in the armature 13 being attracted and the pawls 16 and 24 being brought out of engagement with the teeth 17 of the connecting rod 6 by the spring 22, owing to the fact that the pin 18 on the arm 14 slides along the slanting surface 19. At the same time the contact spring 46 has been brought into contact with the contact spring 45 and an impulse of current has been sent through contact spring 45, contact spring 46, line 60, contact spring 50, contact spring 49, line 61, contact spring 38, contact spring 37, line 62, line 63, the winding of the electro-magnet 25, line 64, line 65 and battery 75. 90 At the same time the armature 26 is thus attracted and the pawl 27 is brought out of engagement with the teeth 29 of the connecting rod 6, which results in the latter starting its 95 downward movement, the frame 3 is tilted and the contact springs 7 and 8 are brought out of contact with the corresponding contact field. The rod 6 now falls down rapidly and it continues to move until the roller 9 100 of the contact spring 10 has found the testing wire of an unoccupied group-selector. If the group-selector is occupied, *i. e.*, the testing wire of the same connected with earth, current passes through contact spring 10, line 66, contact spring 54, contact spring 53 (the contact at 55 is now broken), line 67, line 61, contact spring 38, contact spring 37, line 62, line 63, the winding of the electro-magnet 25, line 64, line 65, and battery 110 75. Consequently, the armature 26 of the electro-magnet remains attracted, *i. e.*, the pawl of the same is held out of engagement with the teeth of the connecting rod. It is to be observed, that the first impulse of current 115 120 125 130

through the electro-magnet 11 must continue for such a long period, that the rod 6, if necessary, can fall down for such a distance, as corresponds to the distance between the 5 first and the last lines of the contact field.

As soon as the contact roller 9 has found an un-occupied line, the said connection is interrupted, and the armature 26 releases and prevents by its pawl 27 the connecting 10 rod 6 from continuing its movement just in the position, which corresponds to the un-occupied line of the group-selector, and at the same time the contact springs 7 and 8 are brought into contact with corresponding 15 contact fields.

The selector is brought to its initial position in the following manner. As the subscriber puts back the receiver at the end of the conversation, an impulse of current is 20 sent through line branch 57, line 69, contact spring 48, contact spring 47, line 70, the winding of the electro-magnet 12, line 71, line 65 and battery 75. The electro-magnet 12 is thus excited and its armature attracted, 25 which results in the contact spring 42 being brought into contact with the contact springs 43 and 44 and the contact spring 40 being brought into contact with the contact spring 41. As the connecting rod has been brought 30 out of its upper position of rest, the contact spring 51 has been brought into contact with the contact spring 52, which is connected with earth, as shown. In this manner a flow of current is effected through contact 35 spring 52, contact spring 51, line 72, contact spring 42, partially through contact spring 43, line 73, the winding of the electro-magnet 12, line 71, line 65, and battery 75, partially through contact spring 44, line 63, the wind- 40 ing of the electro-magnet 25, line 64, line 65 and battery 75. The armature 26 is thus attracted, so that the contact springs 7 and 8 are brought out of contact with the corresponding contact field in the manner de- 45 scribed above, and the armature 26 as well as the armature 20 are now held in attracted position, until the connecting rod 6 has reached its upper position of rest and broken the contact 52, 51. The shifting back (re- 50 turning) of the rod 6 is effected in such manner that an intermittent current is sent from earth through a rotary interrupter 76, line 74, contact spring 41, contact spring 40, line 58, the winding of the electro-magnet 55 11, line 59, battery 75, so that the armature is attracted repeatedly and by means of the lever drum 14 and pawl 16 moves step by step the connecting rod to its upper position of rest, in which the contact 52, 51 is broken, 60 which results in the armatures 20 and 26 being released and the contact 40, 41 being broken and consequently the intermittent current through the electro-magnet 11 interrupted. At the same time the contact springs 65 7 and 8 have been brought into contact with

the corresponding contact fields through the releasing of the armature 26.

In the form of the pre-selector shown in Figs. 2 and 3 a segment 78 provided with teeth 77 is substituted for the connecting 70 rod 6, which segment together with the springs 7, 8 and 10 fixed to the segment and insulated from the same is swung by a spring 79 over the contact field. The said segment 78 and the springs, provided on the 75 same, together with an arm 80, which is fixed to the segment and in the free end of which a stop screw 81 is provided, are fixed on a longitudinally slideable shaft 82, which is acted upon by the armature 26 of the electro- 80 magnet 25 against the action of a spring 83 in such manner, that, as the said armature is attracted, the contact springs 7 and 8 are brought out of contact with the contact field, and the stop screw 81 is brought out of en- 85 gagement with recesses 84 provided in a plate 85. The contact spring 10 is held in constant contact with the contact field. The electrical operations are identical with those described above with reference to the selector 90 shown in Fig. 1. The mechanical operations are as follows.

As the subscriber causes his number switch to operate, the armature 13 is first attracted and the pawls 16 and 24 are brought out of 95 engagement with the teeth 77 of the segment 78 by the spring 22. Owing to the fact that the contact 45, 46 is thereby closed, the electro-magnet 25 is excited and its armature 26 attracted, which, as before stated, results 100 in the contact springs 7 and 8 being brought out of contact with the contact field and the stop screw 81 being brought out of engagement with the recesses 84. The segment 78 and the parts provided on the same are now 105 swung rapidly by the spring 79, until the testing spring 10, in the same manner as stated above with reference to the selector shown in Fig. 1 finds the line of an unoccupied group-selector, in which moment the 110 flow of current through the electro-magnet 25 is interrupted and the segment together with the contact springs are locked by the screw 81, engaging the corresponding recess 84, at the same time as the contact springs 115 7 and 8 are brought into contact with the contact field.

The returning of the selector to its initial position is effected in the manner described above by an impulse of current being sent 120 through the line branch 57 and the electro-magnet 12, so that its armature 20 is attracted and in consequence thereof a flow of current is sent through the winding of the electro-magnet 12 as well as the winding of 125 the electro-magnet 25, which flow of current does not cease until the springs 7, 8 and 10 of the selector have been fully returned through the intermittent flow of current through the rotating interrupter 76 and the 130

electro-magnet 11 and the repeated attracting of the armature 13 resulting therefrom, and the contact 52, 53 has been broken.

Having now described my invention, what I claim as new and desire to secure by Letters Patent is:

1. A selector switch having movable line contacts, a moving device adapted, upon being released, to effect a continuous selective movement of the line contacts, an electro-magnetic driving device adapted to restore the line contacts to normal position, a catching device, an electro-magnet operating said catching device to stop the line contacts in different positions and means operated by the same electro-magnet to move the line contacts out of contact with the contact field.
2. A selector switch having movable line contacts supported by a member slidably journaled in a movable guide and adapted to be moved by gravity, a catching device adapted to stop said member in different positions and an electro-magnet operating said catching device to release the slidable member and at the same time operating said guide to move the line contacts out of contact with the contact field.
3. A selector switch comprising a rocker-frame, a slidable member carried by the rocker-frame, a line selector and line contacts on said slidable member and movable therewith, a movable member carried by said frame for returning said slidable member to its normal position and normally held in engagement therewith, a lock member on said rocker-frame and adapted to engage the slidable member to lock the latter in different positions, means for disengaging said movable and lock members from said slidable member to allow the latter to make a selective movement and to actuate said lock member to rock said rocker frame so that said line contacts will be moved out of the paths of their contact points, means for operating said lock member to lock said slidable member in position upon the selection of said selector and to rock the rocker frame to bring the line contacts in engagement with their selected contact points, means for actuating said movable member to restore said slidable member to normal position and to render said lock member ineffective, said disengagement means being adapted to operate said lock member to rock the rocker-frame, during said restoring operation to bring the line contacts out of the path of their respective contact points, and a second lock member coöoperating with said movable member during the restoration of said slidable member, said lock means being adapted to lock said slidable member in normal position after said restoring operation.
4. A selector switch comprising a slidable member, a line selector and line contacts on said slidable member and movable there- with, a movable member for restoring said slidable member to its normal position and normally held in engagement therewith, a lock member adapted to engage the slid- able member to lock the latter in different positions, means for disengaging said movable member and said lock member from em- gagement with said slidable member to al- low the latter to make a selective movement, means for operating said lock member to 75 lock said slidable member in position upon selection of said selector, means for actuati- 75 g said movable member to restore said slidable member to normal position and to render said locking member ineffective dur- 80 ing said restoring operation, and a second lock member coöperating with said movable member during the restoration of said slid- able member.
5. A selector switch having movable line contacts supported by a member slidably journaled in a movable guide and adapted to be moved by gravity, a catching device adapted to stop said member in different positions and an electro-magnet adapted to 85 85 put the catching device out of action thereby releasing the slidable member and at the same time operating to move the line contacts out of contact with the contact field.
6. A selector switch comprising, a rocker- 85 frame, a slidable member carried by the rocker-frame, a line selector and line contacts on said slidable member and movable therewith, a movable member carried by said frame for returning said slidable mem- 100 ber to its normal position and normally held in engagement therewith, a lock member on said rocker-frame and adapted to engage the slidable member to lock the latter in differ- 100 ent positions, means for disengaging said 105 movable and lock members from said slid- able member to allow the latter to make a selective movement and to actuate said lock member to rock said rocker-frame so that said line contacts will be moved out of the 110 paths of their contact points, means for op- 110 erating said lock member to lock said slid- able member in position upon the selection of said selector and to rock the rocker-frame 115 to bring the line contacts in engagement 115 with their selected contact points, means for actuating said movable member to restore said slidable member to normal position and to render said lock member ineffective, said 120 disengagement means being adapted to op- 120 erate said lock member to rock the rocker- frame, during said restoring operation, to bring the line contacts out of the path of their respective contact points, and a sec- 125 ond lock member coöperating with said 125 movable member during the restoration of said slidable member, said lock means being adapted to lock said slidable member in normal position after said restoring opera- 130 tion.

7. A selector switch, comprising, a slide-
able member, a line selector and line con-
tacts on said slideable member and movable
therewith, a movable member for restoring
5 said slideable member to its normal position
and normally held in engagement therewith,
a lock member adapted to engage the slide-
able member to lock the latter in different
10 positions, means for disengaging said move-
able member and said lock member from en-
gagement with said slideable member to al-
low the latter to make a selective movement,
means for operating said lock member to
lock said slideable member in position upon
15 selection of said selector, means for actuat-
ing said movable member to restore said
slideable member to normal position and to
render said locking member ineffective dur-
ing said restoring operation, and a second
lock member coöperating with said movable 20
member during the restoration of said slide-
able member.

In witness whereof, I have hereunto
signed my name in the presence of two sub-
scribing witnesses.
